BY

Chambelan & Neumann ATTORNEYS.

UNITED STATES PATENT OFFICE.

DAVID HJORTH, OF NEW YORK, N. Y., ASSIGNOR TO THE GENERAL MACHINE & MANUFACTURING CO., OF BRIDGEPORT, CONNECTICUT, A CORPORATION OF CONNECTICUT.

PENDANT SWITCH.

1,421,085.

Specification of Letters Patent. Patented June 27, 1922.

Application filed April 28, 1921. Serial No. 465,124.

To all whom it may concern:

Be it known that DAVID HJORTH, a citizen of the United States, and resident of New York, in the county of New York and State 5 of New York, has invented certain new and useful Improvements in Pendant Switches, of which the following is a specification.

My invention relates to an electric switch mechanism of the push button type and 10 briefly refers to what is commercially known as a pendant switch.

The object of the present invention is to provide an improved and simple form of switch mechanism which can be mounted 15 in a porcelain, enclosed in a metal socket, and adapted to be suspended from a wire, and operated by one hand only manipulating the push button to turn the circuit on and off. Further to design the switch so that the 20 same may be made up inexpensively from punched sheet metal pieces which can be readily assembled to form a comparatively small mechanism that can be mounted within a suitable housing adapted to be positioned 25 within a porcelain block.

Further objects and advantages of the invention will appear in the following specifications and novel features of this device will be further and particularly pointed out 30 in the appending claims, and upon the accompanying drawings forming a part of this specification will be noted similar reference characters to indicate the corresponding parts throughout the several figures and 35 of which,

Fig. 1 shows a side elevation of my improved form of pendant switch as it would 40 appear when enclosed within a sheet metal socket.

Fig. 2 shows a plan view of the switch mechanism including a porcelain block for supporting the same, the sheet metal socket for enclosing the same being omitted.

Fig. 3 is a central vertical section taken on 45 line 3—3 of Fig. 2 illustrating the parts in their normal positions and the armature in position for engagement with the terminals.

Fig. 4 shows a similar side view of the 50 switch mechanism shown in Fig. 3, the operating slide being omitted.

Fig. 5 is a detached side view of the slide and pawl removed from the housing shown in Fig. 4 and as seen from the opposite side of Fig. 3.

Fig. 6 shows a side view somewhat like 55 Fig. 3 but with the push button, slide and connected parts in an operated position.

Fig. 7 shows a central vertical section through the switch mechanism and taken on line 7—7 of Fig. 8, and 60

Fig. 8 shows a side view as seen from the opposite side of Fig. 3.

Referring in detail to the characters of reference marked upon the drawings, 10 represents the shell, 11 the cap, 12 the wires 65 by means of which the complete pendant switch is suspended. 13 indicates the push button and 14 a guide in which the push button is slidably mounted, said guide being provided with fingers 15 having holes 70 whereby the same may be attached with screws to the porcelain block 16 and the housing 19.

17 and 18 represent binding posts and 20 and 21 the terminals in which the posts are 75 mounted and between which the brushes 22 of the armature are positioned to form the circuit through the switch.

The housing is formed of sheet metal and includes a straight back having two opposite side walls 23 and vertical guide flanges 24. The slide 25 is mounted on the guides to reciprocate between the sides and the flanges. The push button is secured to a depending shank 26 of the slide and thus serves as a 85 means to operate the same against the action of the spring 27 mounted upon the pin 28 and having one end engaged at 29 and the other positioned against the stop 30 on a plate 31. 90

The armature 32 is pivoted at 33 to the back 23 of the housing which is provided with stops 34 against which the short end of the armature strikes to limit the movement of the armature. The contact or brush members 22 are insulatively secured to the outer end of the armature and are carried therewith to make and break connections between the two terminals 20 and 21. The armature is actuated by means of a spring 35 mounted 100 upon a stem 36, one end of which is slidably mounted in the outer end of the armature and the other end pivotally connected as at 37 to the rocker member 38.

This rocker member is pivoted to the 105 central portion of the inside of the housing at 33 and is adapted to be thrown forward and backward by the operation of the push

button and connected parts. Pins 39 and 40 are positioned on the near side of this rocker member and adjacent to the outer edge portion and in alignment with the sockets 41 in 5 the forward end of the pawl 42. The pawl is pivoted at 43 to the plate 31 having opposite parallel flanges 44 which engage the inner side of the housing to guide the plate backward and forward when the slide is 10 operated.

A link 45, one end of which is pivoted to the forward end of the slide and the other to the forward end of the pawl serves to operatively connect the two so that when the 15 push button and slide are shoved forward the link, pawl and plate will likewise be carried forward in a direct line so that the pocket in the forward face of the pawl will engage the nearest of the pins 39 or 40 to 20 throw the rocker member, and further so that when the push button is released, the spring 27 which is in engagement with the pin 30 on the plate 31 will force the latter, together with the slide, back to their lower 25 or normal position. This causes the pawl and link to swing, as indicated in dotted lines in Fig. 5, so as to pass the pin on the rocker member which has been positioned for engagement by the next operation.

30 By reason of the use of the plate 31 which fits against the slide we are enabled to obtain a flexible connection between the pivotal point 43 for the pawl and the pivotal connection of the link to the slide and whereby 35 by the said pawl is free to swing from one side to the other as is necessary to pass the pins 39 and 40 on its return movement. It will further be noted that by reason of the notch 46 formed in the upper portion of the 40 plate ample room is provided in which to position the link and whereby the end thereof which is pivoted to the pawl is free to swing to the extent necessary to afford the pawl the required movement.

45 From the foregoing it will be seen that the normal positions of the parts are shown in Fig. 3 and that by simply pressing upon the push button 13, the slide 25, the link 45, pawl 42 and plate 31 are all carried up 50 against the resistance of the spring 27. This movement causes one of the sockets 41 in the pawl to engage the nearest pin 40 on the rocker member, see Fig. 4, and serves to move the same forward and to rock the 55 member until its pivotal pin 37 is carried over the center. This compresses the spring 35 and causes it to throw the armature back as shown in Fig. 6. When the push button is released the slide and connected parts re- 60 turn to their lower and normal position, when a further operation will obviously throw the armature in the reverse direction.

Having thus described my invention, what I claim and desire to secure by Letters 65 Patent, is

1. In a pendant switch of the class described, the combination of a housing, a slide mounted in the housing and having a push button attached thereto, a rocker member pivotally attached to the housing, an armature also pivoted to the housing, a flexible connection between the rocker member and armature whereby the latter is thrown backward and forward by the rocker movement of the latter, a double acting pawl for 75 engaging and operating the rocker member, a link one end of which is connected to the slide and the other end to the pawl, and whereby the pawl is carried with the slide, and a spring for returning the pawl and 80 slide to their normal position.

2. In a pendant switch of the class described, the combination of a porcelain block and means for enclosing and supporting the same, of a housing positioned therein, 85 a slide mounted in the housing and having a depending shank and a push button attached thereto, a rocker member pivotally attached to the housing, an armature also pivoted to the housing, a flexible connection between the rocker member and armature whereby the latter is thrown backward and forward by the rocker movement of the latter, a plate positioned against the slide and adapted to be carried thereby, a double action pawl pivotally connected to the plate, 90 a link one end of which is connected to the slide and the other end to the pawl and whereby the pawl and plate are flexibly carried with the slide, and a spring for returning the plate and slide to their normal position. 100

3. In a pendant switch of the class described, the combination of a housing, a slide mounted in the housing and having 105 means for actuating the slide, a rocker member pivotally attached to the housing, an armature also pivoted to the housing, a flexible connection between the rocker member and armature whereby the former is thrown backward and forward by the movement of the latter, a double acting pawl for engaging and operating the rocker member, a link one end of which is connected to the slide and the other end to the forward end of the 110 pawl, means for guiding the lower end of the pawl, and a spring for returning the pawl and slide to their normal position.

4. In a pendant switch of the class described, the combination of a housing, a slide mounted in the housing and having a push button attached thereto, a rocker member pivotally attached to the housing, an armature also pivoted to the housing, a flexible connection between the rocker member and armature whereby the latter is thrown backward and forward by the rocker movement of the latter, a plate positioned against the slide, a pawl pivotedly connected to the plate and adapted to engage 125 130

and operate the rocker member, a pivotal connection between the slide, pawl and plate and whereby the pawl is carried forward to throw the rocker member, and a spring for 5 returning the plate and slide to their normal position.

Signed at New York in the county of New

York and State of New York this 9th day of April, A. D., 1921.

DAVID HJORTH.
